UNITED STATES PATENT OFFICE.

ALFRED OBERLE, OF KANSAS CITY, MISSOURI, ASSIGNOR OF ONE-HALF TO THOMAS E. SCOFIELD, OF KANSAS CITY, MISSOURI.

PROCESS FOR RECOVERING VANADIUM FROM PETROLEUM HYDROCARBONS.

No Drawing.

Application filed September 8, 1925. Serial No. 55,171.

This invention relates to improvements in a process for recovering vanadium from petroleum hydrocarbons, and refers more particularly to a process in which compounds of vanadium are extracted from petroleum products.

This application is a continuation in part of a previous application Serial No. 722,309 filed June 25, 1924.

10 In my previous application I described a process for recovering vanadium from petroleum residue such as petroleum coke and heavy residual oils or carbonaceous materials such as cokey substances resulting from the 15 cracking of petroleum hydrocarbons. The present process has to do primarily with a method of extracting vanadium by consumption of the volatile and oxidizable petroleum products by the action of heat, the 20 vanadium being recovered as an oxide or other vanadium compound by deposition.

In my prior application, I described the process of leaching the vanadium compounds from the petroleum residue with a vanadium 25 solvent, but where vanadium is desired to be recovered from certain hydrocarbon oils which are to be burned as fuel, as certain of the heavy Mexican, Ohio or Persian oils, the hydrocarbon products are practically 30 completely consumed in the combustion of the oil and to recover the vanadium compounds, it is necessary to devise some method of obstructing or retarding the metal compounds by means of a deposit screen or by 35 the use of an absorptive agent such as coke, cinders, activated carbonaceous material, ground or broken up slag, spent shale, diatomaceous earth or other absorptive substances which would serve to extract the 40 vanadium compounds from the combustion gases. Subsequent to this separation, the vanadium compounds may be dissolved from the absorbent material.

In experimenting with hydrocarbons, it 45 has been my experience that the vanadium compounds are usually more prevalent in the poorer grades of oil, i. e., those oils having a high sulphur content such as the Mexican oils, particularly Panuco crude, Persian 50 crude and certain of the high sulphur bearing Ohio oils. These oils do not make particularly good cracking stock and are, to a considerable extent, used as burning oils

so that the recovery of vanadium compounds is best effected by a process in which during 55 the consumption of the oil vanadium compounds which may be carried off mechanically in the form of fine particles in the combustion gases, are arrested and deposited in an absorbent body or upon specially prepared wire screens or any other type of obstruction devices which effectively prevent 60 the passage of the metallic vanadium and cause the same to be deposited in the absorbent material to be later recovered by extraction with a solvent.

An absorbent material is used with the best effect by being interposed in the form of a tower in the path of the combustion gases so that the gases are directed through 70 the tower and through the absorbent material in their travel to the stack or atmosphere.

Where oils containing vanadium are used in internal combustion engines, such as 75 heavy types of Diesel engines, any vanadium content may be recovered from the exhaust gases by interposing an absorbent body of activated carbon coke or other relatively inert absorbent materials in the exhaust line. 80 The vanadium is normally deposited as a vanadium oxide which is easily dissolved from the absorbent material with a proper solvent.

Among other absorptive materials which 85 have been found effective in the recovery of this material are kaolins, such as bauxite, and colloidal clays, including bentonite and other hydrous aluminum silicates.

The process affords a potential source of 90 metallic vanadium which may be extracted in a relatively pure state by simply exhausting the hydrocarbon materials from the oil by combustion and extracting the metallic vanadium by deposition of the metallic compounds in an absorbent body and subsequently dissolving the metallic compound 95 from the absorbent material.

I claim as my invention:

1. A process for recovering vanadium 100 from petroleum hydrocarbons, consisting in exhausting hydrocarbon products by combustion and collecting the deposited vanadium compounds in an absorptive material.

2. A process for recovering vanadium 105 from petroleum hydrocarbons, consisting in

exhausting hydrocarbon products by combustion and collecting the deposited vanadium compounds in an absorptive material and extracting the vanadium compounds therefrom.

3. A process for recovering vanadium from petroleum hydrocarbons, consisting in

exhausting hydrocarbon products by combustion and collecting the deposited vanadium compounds in an absorptive material and dissolving the vanadium compounds from the absorptive material with a solvent.

ALFRED OBERLE.
